A cross-sectional diagram of a rotating burner assembly. The diagram shows a central circular component with various numbered parts: 34, 33, 32, 27, 3, and 1. This central part is surrounded by a ring of smaller circles labeled 1. The outermost boundary is a thick, hatched ring labeled 1. Several labels with leader lines point to specific parts: 'ROTATING BURNER' points to the central assembly; 'STILL PIPES OR CONTAINERS FOR SUBDIVIDED BODIES OF OIL.' points to the outer hatched ring; 'BURNER DRIVE MEMBER' points to a small assembly on the right; and '1' points to a small circle on the left. Arrows indicate the direction of rotation for the central assembly.

A technical diagram of a gas burner assembly. The diagram shows a vertical tube assembly with a U-shaped section. The top part is labeled 'GAS' and 'AIR' entering from the left. Number '21' is on the vertical section. Number '27' is on the left side of the U-shaped section. Number '27a' is on the right side of the U-shaped section. Number '28' is on the bottom left. Number '29' is on the bottom left. Number '30' is on the right side of the U-shaped section. Number '31' is on the bottom right. Number '32' is on the top right. Number '33' is on the top right. Number '34' is on the top right. A handwritten label 'sys. 3.' is written diagonally across the top right of the diagram.

FRANK E. WELLMAN, OF KANSAS CITY, KANSAS, ASSIGNOR TO THE KANSAS CITY GASOLINE COMPANY, OF KANSAS CITY, KANSAS, A CORPORATION OF KANSAS.

METHOD OF CRACKING OIL.

Application filed July 10, 1922. Serial No. 574,041.

My invention relates to cracking processes for transforming heavy hydrocarbons having a high boiling point into other hydrocarbons having a lower boiling point. It has for its object the improvement of the process disclosed in my prior co-pending application, Serial Number 532,873, filed January 30, 1922, in which heat is applied in constant rotation around a unitary body of oil in a vertical container, at such a rate of progression that no one area receives the full application of the source for a long enough period to destructively affect the container, while at the same time a high temperature is employed at the point of application of the source, for efficiency in driving in the heat energy and causing it to penetrate the oil for cracking purposes. The active cracking zone is found within a limited area of penetration, and it is therefore important to include within it as large a percentage of the whole body of oil under treatment as possible, by increasing the heating surface.

In my prior copending application, Serial Number 565,633, filed June 3, 1922, I have disclosed an apparatus in which the heating surface is largely increased proportionately to the mass of oil under treatment, by using a circular series of pipes as containers, with headers and expansion tanks to prevent foaming, and a rotating burner system in which a trailing flame is applied periodically to each pipe. The cracking zone is thus largely increased, and it is evident that the method of heating involved might be practiced with various forms of apparatus, not necessarily included within the claims of said application, Serial Number 565,633. Hence the purpose of the present application is to present the method above referred to and claim the same without limitation to any particular apparatus. As said method is disclosed in the foregoing application, this case is a continuation in part thereof.

Briefly stated, my improved process contemplates extending the body of oil under treatment so that its superficial area available for application of heat externally becomes large in proportion to its mass, and particularly so that the greater proportion of its volume lies within the cracking zone of direct heat penetration; the extension being in some symmetrical of other figure such that a high temperature source may be

applied or a high temperature created, over, in or through one circumscribed portion after another of the extended body with the result that cracking energy is driven in under most favorable conditions, at high efficiency, without destructive action on the container or containers of whatever nature they may be.

Forms of apparatus, both as to the still and as to the heating means, may be varied quite widely without departing from this process. I have chosen and shall describe herein the circular pipe still and the rotating burner of my prior copending application, Serial No. 565,633, as the best form known to me at the present time, but contemplate modifications thereof including circulating coils leading from the upper part of a main sill to the lower part thereof and with their turns arranged in any figure that permits a flame or other source of heat to be applied to them in rotation periodically. It should also be noted that various other sources of heat, such as radiant energy or electrical energy may be applied in rotation in the same manner, as for example by having electrical heating elements heated to incandescence in the several pipes in rotation, or by using a travelling arc or circular series of intermittent arcs or heat induced by a rotating electrical field in the several pipes in rotation. Many other modifications in both the form of container and the specific heating means will occur to those skilled in the art; and all of these are within the scope of my present invention though not specifically claimed herein.

The preferred form of apparatus for practicing my invention is illustrated in the accompanying drawings, in which:

Fig. 1 is a vertical section on the line 1—1 of Fig. 2;

Fig. 2 is a transverse section on the line 2—2 of Fig. 1; and

Fig. 3 is a detail sectional view on an enlarged scale of the burner, its supporting shelf and associated parts.

Referring to the drawings, 1 designates a series of vertical still pipes, which may be for example 7 inches in diameter and approximately 40 feet in length. These are arranged in a circle, being supported preferably at their upper ends. 3 is an inner wall or liner of refractory material, in the form of a frustum of an inverted cone. 4

is the outer furnace wall of the same material in the form of the frustum of an upright cone. It is to be observed that in cross section at any point these inner and outer walls are circular as shown in Fig. 2.

At their lower ends, the still pipes 1 are all secured to a ring manifold 5, from which draw-off pipes 6 are led out through the furnace walls 4. At their upper ends the still pipes are closed by flanged and bolted cap plates 7, or other suitable means, these being removable for cleaning purposes, but in practice I may use a header or manifold for all these pipes similar to the lower ring 5 in Figs. 1 and 2, and in such case, one or both of the manifolds at top and bottom may be made large enough to permit the entrance of workmen for cleaning out the pipes.

Inasmuch as the still pipes have very considerable content by reason of their length, but a very small surface for the yielding up of vapor, it is necessary to provide means for preventing foaming, which I do in the form of tanks 8^a—8^b. These tanks are connected to the still pipes by radial tubes 9—10, the former lying below the normal liquid level and the latter lying above it. In addition to these connections, the tanks 8^a and 8^b, are connected by pipes 11 containing expansion joints 12 with the central equalizing and feeding tank 13. Below the liquid level this is connected to all of the still pipes by radial tubes 14. A gauge glass or other convenient form of indicator 15 is provided to show the liquid level in the tank 13.

The usual vapor line and make-up or feed pipe connections are shown at 16 and 17, connected to the tank 13, from which the feed of fresh material is equalized to all of the still pipes and the liquid level maintained the same throughout the system.

The fuel feed and burner mechanism is marked 18, 19, 20, 21, and 34. The pipe lengths 18, 19 and 21 are double, that is to say an oil pipe is secured concentrically within the steam pipe, so that at the burner 34 oil and steam are both supplied as determined by suitable valves connected to the supply pipe 18. Centralized with respect to the still is a swivel joint 23, the outer section of which is connected to the pipe 19 and is rotated by means of a crown tooth gear 22 and gear 24 driven by shaft 25 carrying a sprocket wheel 26. The pipe section 21 drops through an annular slot in the guard plate 20, closing the annular opening 20^a in the top of the furnace. The lower end of the pipe 21 (see Fig. 4), passes through an opening in the rotating shelf 27 where a bend is produced to form a trailing burner arm 28, (see Figs. 2 and 3), which carries a burner composed of a pair of feeder arms 33 and 35, one carrying oil and the other steam, and a burner head 34.

The arms 33 and 35 are connected to the inner and the outer pipes, respectively, of the concentric pair 18—19—21.

The burner arm 28 lies beneath the shelf 27, its end passing up through an opening therein and carrying a T-fitting 32 to which the arms 33 and 35 are secured. The shelf 27 is annular, pierced with air openings 27^a, adjacent the burner, and has depending annular flanges 29 each dipping into liquid 31 in an annular trough 30, constituting the top member of an hermetically sealed enclosure 39, which communicates with the outer air through pipe 40, (see Figs. 1 and 2), the volume of air supply being regulated by means such as the damper 41, controlled as by an operating rod 42 from the outside. The chamber 39 is of such size and shape that workmen may enter it through a suitable manhole for adjustment of the burners. When the still is in operation the air chamber and surrounding parts are cool, even the brick work in walls 3 and 4 remaining dark and at a low temperature compared with that of cracking stills as ordinarily fired.

The burner system, including the shelf 27, is rotated at a regular rate of speed by top and bottom gears. At the top, gear 24 is carried on shaft 25, fitted with sprocket 26. At the bottom the gear 36 meshes with crown teeth around the outer edge of shelf 27, and is driven through the shaft 37 by motor 50, which also drives the upper shafts 25 through sprocket chain 38 or equivalent means. By suitably relating the worm sprockets, gears and motor, the entire system is rotated at a uniform speed and without racking or strain, the top guard plate sliding around the top of the furnace and pivoting at the joint 23. The shelf 27 may of course be given additional bearing support in or out of the troughs 30, and the down pipe 21 may be duplicated at 180° around the shelf to give a hanging frame, if desired. The specific arrangement of the burner system is immaterial so long as it performs the functions described. The burner throws its flame across the inner sides of the still pipes 1, around which it is rotated at such a rate of speed that any given spot in any still pipe is within the directly heated area during each cycle of rotation, for a period less than that in which destructive heating would occur. Since the air supply to the annular combustion space is only by way of openings 27^a, there is no admixture of atmospheric air with the products of combustion, and the furnace temperature and operating conditions therein, are therefore both uniform and efficient. This effects a substantial saving in fuel, and also produces a more uniform output.

Having thus described means for practicing my invention, the advantage gained

by this method of subdivision when combined with rotary or other periodic heating, is apparent. The active zone in which sufficient heat energy for cracking penetrates 5 the oil extends inward a limited distance from the heated shell of the still or retort. Assuming this to be say two inches, and that a six inch pipe be employed, the cross sectional area of the zone efficiently penetrated 10 is greater than the area of the central unpenetrated zone. To heat efficiently, a high temperature source must be employed, and to prevent destructive effects as well as to uniformly distribute the heat, periodic inter- 15 ruptions of the heating and cyclic applications thereof must be produced. I wish it distinctly understood, however, that the present invention is in no way limited to the specific apparatus described, but that it may 20 be practiced with any form of apparatus, and with any source of heat, which satisfies the requirements hereinbefore laid down.

In this connection it should be noted that where a pipe still or the equivalent is em- 25 ployed, the pipe arrangement or figure adopted must be such in any case that periodic application of heat can be made over the surface of the oil in each pipe in succession. This symmetrical arrangement 30 of units may be for example, in a straight line with an oscillating flame, in a vertical cylinder with an inwardly pointing radial

or tangential flame, (either the cylinder or the flame rotating), or as in my prior application hereinbefore referred to, in a circle 35 of pipes heated by a rotating trailing flame.

Where radiant energy produced by combustion or by electricity is employed, it may similarly be applied to the oil in each pipe in succession; and where a rotating electro- 40 magnetic field or the equivalent is used, the Foucault or eddy currents relied on in the short circuited secondary of the pipe walls must be induced in such an area as to heat practically the entire content of the pipes. 45

I claim:

The method of cracking hydrocarbon oil which consists in dividing the main body of oil under treatment into a plurality of connected bodies whereby the area available 50 for the external application of heat is proportionately increased, intermittently and individually heating said separated bodies in periodic rotation whereby a degree of heat greater than could be withstood if continu- 55 ously applied may be employed without de-structive action, and drawing off the result-ant vapors from all the bodies in common while maintaining a common liquid level with extended surface to prevent foaming 60 in the individual bodies.

In testimony whereof I hereunto affix my signature.

FRANK E. WELLMAN.
